UNITED STATES PATENT OFFICE.

ARTHUR MARSDEN, OF MIDDLESBROUGH, ENGLAND.

COIN-FREED AUTOMATIC DELIVERY-MACHINE.

No. 833,888.

Specification of Letters Patent.

Patented Oct. 23, 1906.

Application filed October 21, 1904. Serial No. 229,413.

To all whom it may concern:

Be it known that I, ARTHUR MARSDEN, a subject of the King of Great Britain and Ireland, residing at Middlesbrough, in the county of York, England, have invented a new and useful Improvement in Coin-Freed Automatic Delivery-Machines, of which the following is a specification.

This invention relates to a silent coin-freed automatic delivery apparatus for supplying sweets, chocolates, programs, and other small articles or packets, and is intended mainly for use in theaters, music-halls, and other places of amusement, the said apparatus being adapted for attachment to the back of each seat or in any other convenient position, so as to provide a separate supply for each occupant, and being so arranged that the complete machine or apparatus shall be of such diminutive proportions as to occupy only an exceedingly small space, thereby enabling the apparatus to be attached without interfering to any appreciable extent with the comfort of the occupants of the seats.

In constructing my improved apparatus or machine I employ a flat box or casing preferably about three-quarters of an inch in thickness, having in its rear part a chamber (or series of such chambers) containing the article or articles offered for sale. The front of the casing is partitioned off to form a narrow chamber, which serves as a coin-chute and also contains the actuating mechanism. The coin is inserted through a slot in the upper part of this chamber and passes down an inclined chute until it comes into contact (direct or indirect) with a flat spring, which is inclosed, preferably, in a small chamber at the end of the casing. This spring is adapted to engage with a catch carried by the door, lid, or sliding drawer of the delivery-chamber, thereby locking the said delivery-chamber, and is adapted to be depressed (thereby releasing the said door, lid, or sliding drawer of the delivery-chamber) on pressure being applied to the coin within the chute. This pressure may be applied by means of a small pivoted spring-lever or cam provided in the upper part of the coin-chamber and having a thumb-piece projecting from the top or side of the machine, or it may be applied by any other approved means.

My invention is illustrated in the accompanying drawings, in which—

Figure 1 is a front elevation, Fig. 2 a side

elevation, and Fig. 3 a plan, of one form of the machine. Fig. 4 is an elevation, and Fig. 5 a plan, (inverted,) of a somewhat-modified form of the machine.

Referring to Figs. 1, 2, and 3, A is the delivery-chamber, and B the small coin-chamber containing the actuating mechanism, which comprises, essentially, a pivoted lever or cam C, a pivoted catch-lever D, and a spring E. The chamber A is closed by means of a hinged lid F, which is secured in position by means of a catch G thereon engaging with the hooked end H of the lever D. The coin-chamber B and also the lower end of the delivery-chamber A is closed by means of a hinged door I, having a catch J, which is adapted to engage with the lock K, which may be of any ordinary type. The *modus operandi* is as follows: The coin is inserted through the slot L and drops down the chamber B to the position M, where it comes into contact with the lever D and the cam C. The cam C is then moved over to the position C', this action depressing the coin to the position M', where it is securely held between the lever D and the side of the casing, and at the same time forcing back the lever D to the position D' and locking it in that position so long as the coin remains in the machine. This movement of the lever D releases the catch G of the door F, allowing the contents of the chamber A to be withdrawn. The upper end of the lever D when moved to the position D' projects under the slot L and partially obstructs it, (see Fig. 3,) thereby guarding against the insertion of a second coin so long as the first coin remains in the machine. The coin is removed by way of the door I when the machine is recharged by the attendant.

Referring to Figs. 4 and 5, in this case the actuating mechanism is similar to that described above with reference to Figs. 1, 2, and 3, but the hinged lid F is arranged at the lower end of the delivery-chamber A instead of at its upper end. The coin-chamber B is closed by means of an independent pivoted bar I, having a catch J, adapted to engage with the lock K, as hereinbefore described.

The lever D is arranged to obstruct the coin-slot when a coin has been inserted and the contents of chamber A removed, because the lid F usually closes by gravity or it is closed by the purchaser after removing the goods. It is not desirable that other coins should be inserted after the contents of the

chamber A have been removed, and the device is so arranged that the coin-slot is obstructed until the coin first inserted has been removed and the chamber A refilled with 5 goods.

What I claim as my invention, and desire to secure by Letters Patent, is—

The combination, with a chamber for the goods, and a coin-chamber arranged side by side; of a spring-pressed catch-lever pivoted in the said coin-chamber and provided with a hook at its upper end, a cover hinged to the said chambers and provided with a coin-slot and a catch, said slot being unobstructed 15 when the said catch is engaged by the said

hook and being obstructed by the said hook when the said catch is released, and a pivoted presser member arranged partially inside the said coin-chamber and operating to press the coin against the lower part of the said catch-lever to unlock the said cover and to subsequently hold the said hook in a position to obstruct the said coin-slot. 20

In testimony whereof I have signed my name to this specification in the presence of 25 two subscribing witnesses.

ARTHUR MARSDEN.
